LIFESAVING GARMENT

Leonard R. Temple, Rosslyn, Va., assignor to
Temple Safety on Sea Corporation, Rosslyn,
Va., a corporation of Delaware

Application November 25, 1936, Serial No. 112,789

7 Claims. (Cl. 9—20)

The present invention relates to life-preserving appliances, and aims to provide a novel and improved garment of water-proof material that completely envelops the body and limbs of the wearer for protection against exposure and for supporting the wearer in an upright manner with his head above the water when cast adrift in case of shipwreck, or the like.

Another object of the invention is to provide a garment of the above indicated character having an opening at the neck of sufficient size to permit the wearer to get into the same, said garment being of a construction and arrangement so that it may be completely sealed about the neck to keep the wearer dry and to retain the heat generated by his body within the garment protecting him from exposure.

A further object of the invention is the provision of a water tight garment having weights at the foot portions thereof to hold the feet of the wearer downward, and having a sufficient quantity of buoyant material attached to the body portion of the garment to hold the wearer afloat, said positioning and association of the weights and buoyant material will support the wearer in an upright vertical position with his head and shoulders above the water.

It is also an object of the invention to provide a garment of character indicated, which is simple and substantial in construction, which may be manufactured economically, and which will be thoroughly efficient and practical in use.

With the foregoing and other objects in view, which will be apparent as the description proceeds, the invention resides in the construction and arrangement of parts, as hereinafter described and claimed; it being understood that changes can be made within the scope of what is claimed, without departing from the spirit of the invention.

The invention is illustrated in the accompanying drawings, wherein:

Figure 1 is a perspective view of my improved garment, showing the same in position for use,

Figure 2 is a similar view of the upper portion thereof, showing the same open prior to use,

Figure 3 is a view similar to Figure 2 illustrating the neck opening partially closed,

Figure 4 is a fragmentary vertical section through the collar band,

Figure 5 is a horizontal section through the neck portion in the position shown in Figure 3, and

Figure 6 is a cross section taken on line 6—6 of Figure 1.

Referring to the drawings the numeral 10 designates the torso or body enclosing portion of the garment having attached or formed a part thereof the leg portions 11, which extend downwardly and also form the foot enclosing portions 12. Attached to, or positioned within the foot portions 12 are weights 13, each being of substantially three pounds. The manner of forming the foot portions 12 and of affixing the weights 13 is such that said foot portions are water-tight.

At the shoulder portions of the main body portion 10 are attached sleeves 14, which may be formed with the same material forming the body portion 10. The ends of the sleeves 14 are closed in a water-tight manner and in form to provide mittens 15. Under the arm pit portions of the garment and attached to the opposite sides of the body portion 10 are sections of buoyant material 16, which extend downwardly to substantially the hip portions of the garment.

The neck band 17, which is attached to the body portion 10, as at 18, is of tubular construction, having an inner wall 19 and outer wall 20 connected together by a rolled upper portion. The neck band is open in the front, as at 21, and has arranged therein between the inner wall 19 and outer wall 20 a substance of soft compressible material, such as sponge rubber, or the like, 21. The outer wall 20 of the neck band 17 is slit a short distance from the open front portion 21 thereof, at each side thereof, as at 22, through which extends a fabric strap 23. Each end of the strap 23 is positioned exteriorly of the neck or collar band, while the intermediate portion of the strap extends through the slits 22 and is arranged between the outer wall 20 and the sponge rubber 21. On one end of the strap 23 is a buckle 24 for connecting the ends of the strap together to hold the collar band 17 about the neck of the wearer in a snug manner.

Extending downwardly from the front open portion of the collar band 17 is a placket 25, which terminates at substantially what would be the waist line, as illustrated in Figure 3 of the drawings. Attached to the front of the body portion 10 and outer wall 20 of the collar band forwardly of the slits 22 in said outer wall and spaced from the placket 25 is a gore 26. Said gore 26 is also attached to the body portion 10, by means of stitching or the like, below the placket 25 so as to form water-tight connection of the gore 26 with the body portion 10 and collar band 17. The gore 26 is of considerable fullness and together with the placket 25 provides an opening of sufficient size to permit a person to enter the

garment at such point. It will be noted by referring to Figures 2 and 3 that the upper free edges 21 of the gore 26 extend a considerable distance above the collar band 17, the purpose of which will be set forth as the description proceeds.

Also attached to the front of the body portion 10 at the same opposite side attachment of the gore 26 to the body portion 10 are lapels 28 and 29, which have attached thereto respective portions of adjustable fasteners 30 for attaching said lapels together.

When the garment is to be used the same is arranged in the position illustrated in Figure 2, so as to provide an opening of sufficient size to permit a person to enter the garment through the neck opening and placket. After the person is in the garment the material forming the gore 26 is gathered in, either by pleating or any other manner and the strap 23 is fastened together exteriorally of the material forming the gore with the collar band 17 snugly secured about the neck of the wearer, as illustrated in Figure 3 of the drawings. The gathered in or pleated portion of the gore 26 above the strap 23 is folded downwardly over said strap 23 and the lapels 28 and 29 are folded together and fastened by the adjustable fasteners 30 for holding the material of the gore 25 that has been folded over the strap 23 under said lapels and for holding the body portion 10 at opposite sides of the placket 26 together about the body of the wearer.

With this arrangement it can be seen that the strap 23 first closes the open portion of the gore 26 and that the lapels 28 and 29 again close the open portion of said gore so as to prevent to the greatest degree the possibility of water entering into the garment through the gore opening. Also for preventing water from entering the garment the soft compressible sponge rubber will perfect a seal about the neck of the wearer irrespective of the fact persons necks are of various sizes, as one end of the collar band may be lapped over the other, compressing the sponge rubber throughout the area of overlap, as illustrated in Figure 5.

45 Figure 5. By providing the weights at the foot portions of the garment and the buoyant material at the sides of the body portion of said garment the person wearing the same will be supported in the water in a vertical upright manner with his head and shoulders above the water. Due to the manner in which the opening in the gore 26 is closed and the manner the collar band is sealed about the neck of the wearer, not only is water excluded from the interior of the garment, but the body temperature of the wearer will generate sufficient heat within the garment to keep the person comfortable even though he is adrift in water of a considerable low degree.

60 Having thus described my invention, what I claim as new is:

claim as now set forth:

1. A lifesaving garment, comprising a body and limb enclosing portion having a neck opening therein and a placket extending into said neck opening, an upstanding collar at said neck opening, a gore arranged exteriorly of the body portion and attached to said body portion about said placket with its upper portion open, said gore extending above the collar and being attached thereto, and means carried by said collar for holding said collar snugly about the neck of a wearer and for closing the upper portion of the gore by holding said upper portion of said gore snugly between the collar and the said means.

75 2. A lifesaving garment, comprising a main

body portion having a neck opening therein and a front opening extending into said neck opening, a collar at said neck opening and being open at the front opening of the garment, a gore arranged exteriorly of said main body and attached thereto and to said collar about said front opening and having its upper portion open and extending above said collar, a member about said collar for holding the same to the neck of the wearer and to close the upper portion of the gore by clamping the same between the collar and said member, a pair of lapels one arranged at each side of said opening, and means attaching said lapels together over said gore. 5 10

3. A lifesaving garment, comprising a main body portion having a neck opening therein and a front opening extending into said neck opening, a collar at said neck opening and being open at the front opening of the garment, a gore arranged exteriorly of said main body and attached thereto and to said collar about said front opening and having its upper portion open and extending above said collar, a member about said collar for holding the same to the neck of the wearer and to close the upper portion of the gore by clamping the same between the collar and said member, a pair of lapels one arranged at each of said front opening, and means attaching said lapels together over said gore, said upper portion of said gore above said collar being folded over said clamping member and extending downwardly under said lapels. 15
20
25
30

under said lapels.

4. A lifesaving garment, comprising a main body portion having a neck opening therein and a placket extending into said neck opening, a 35 collar of tubular formation attached to said main body portion at said neck opening and terminating at said placket, a soft compressible substance arranged in said tubular collar, a gore arranged exteriorly of the main body and attached there to about the placket, said gore also being attached to the collar and extending above same, and a member positioned about the soft compressible substance in the collar to hold the collar to the neck of the wearer and to engage the 40 upper portion of the gore for closing the same. 45

upper portion of the gore for closing the same. 50
5. A lifesaving garment, comprising a main body portion having a neck opening therein and a placket extending into said neck opening, a collar of tubular formation attached to said main body portion at said neck opening and terminating at said placket, a soft compressible substance arranged in said tubular collar, a gore arranged exteriorly of the main body and attached thereto about the placket, said gore also being attached to the collar and extending above same, the outer wall of said tubular collar having slits therein one at each side of the gore, and a strap having the intermediate portion thereof positioned between the soft compressible substance and the outer wall of the tubular collar while its ends extend outwardly of the collar through said slits, the ends of said strap being connected together for holding the collar to the neck of the wearer and for engaging over the upper portion of the gore for closing the same. 65 60

portion of the gore for closing it.

6. A lifesaving garment, comprising a main body portion having a neck opening therein and a placket extending into said neck opening, a collar of tubular formation attached to said main body portion at said neck opening and terminating at said placket, a soft compressible substance positioned in said tubular collar, a gore arranged exteriorly of the main body of the garment and attached thereto around the placket, 75

said gore also being attached to the collar and extending above same, a strap carried by the collar and outwardly of the soft compressible substance for holding the collar snug to the neck
5 of the wearer and for engaging over the upper portion of the gore to close the same, said gore having its upper portion folded over said strap and extending downwardly, a pair of lapels attached to the main body one at each side of
10 said gore, and adjustable fasteners on said lapels for attaching the same together over the main portion of the gore and over the down turned upper portion of the gore.

7. A lifesaving garment, comprising a body and

limb enclosing portion having a neck opening therein and a placket extending into said neck opening, a gore formed about said placket and extending above said neck opening, a member at said neck opening for holding the neck portion thereof about the neck of a wearer and for closing the upper portion of the gore, said gore having its portion above said neck opening folded over said member and extending downwardly, and means on said garment engaging said folded-
5 over portion of said gore for holding the same
10 in downwardly extending position.
